(57) CLAIM

The ornamental design for a shirt with rear pocket as shown and described.

DESCRIPTION

FIG. 1 is a perspective rear view of a shirt having a rear pocket in accordance with a first embodiment of the present invention;

FIG. 2 is a rear view of a shirt having a rear pocket in accordance with a first embodiment of the present invention; FIG. 3 is a left side view of a shirt having a rear pocket in accordance with a first embodiment of the present invention; FIG. 4 is a right side view of a shirt having a rear pocket in accordance with a first embodiment of the present invention; FIG. 5 is a top view of a shirt having a rear pocket in accordance with a first embodiment of the present invention; FIG. 6 is a bottom view of a shirt having a rear pocket in accordance with a first embodiment of the present invention; FIG. 7 is a perspective rear view of a shirt having a rear pocket in accordance with a first embodiment of the present invention;

FIG. 8 is a perspective rear view of a shirt having a rear pocket in accordance with a second embodiment of the present invention.

FIG. 9 is a perspective rear view of a shirt having a rear pocket in accordance with a second embodiment of the present invention;

FIG. 10 is a rear view of a shirt having a rear pocket in accordance with a second embodiment of the present invention;

FIG. 11 is a left side view of a shirt having a rear pocket in accordance with a second embodiment of the present invention;

FIG. 12 is a right side view of a shirt having a rear pocket in accordance with a second embodiment of the present invention;

FIG. 13 is a top view of a shirt having a rear pocket in accordance with a second embodiment of the present invention; and,

FIG. 14 is a bottom view of a shirt having a rear pocket in accordance with a second embodiment of the present invention.

Broken lines shown in the drawings illustrating portions of the shirt with rear pockets in FIGS. 1-14 and the balls in FIGS. 7 and 14 form no part of the claimed design.

1 Claim, 14 Drawing Sheets
